[57] CLAIM

The ornamental design for a sports shoe, as shown and described.

DESCRIPTION

FIG. 1 is a front elevational view thereof;

FIG. 2 is a rear elevational view thereof;

FIG. 3 is a top plan view thereof;

FIG. 4 is a bottom plan view thereof;

FIG. 5 is a right side elevational view thereof; and,

FIG. 6 is a left side elevational view thereof.

The design is symmetrical in respect of the corresponding opposite sports shoe.
